[57] CLAIM

The ornamental design for a hockey glove, as shown and described.

DESCRIPTION

FIG. 1 is a left side elevational view of a hockey glove showing my new design;

FIG. 2 is a front elevational view thereof;

FIG. 3 is a right side elevational view thereof;

FIG. 4 is a rear elevational view thereof;

FIG. 5 is a top plan view thereof;

FIG. 6 is a bottom plan view thereof;

FIG. 7 is a rear elevational view of a second embodiment thereof; the shaded portions indicating contrast; and,

FIG. 8 is a left side elevational view thereof, the shaded portions indicating contrast.

The crosshatch shading in all views is understood to repeat throughout the indicated area. The missing views for the second embodiment are the same as FIGS. 2, 3, 5 and 6 except for the showing of contrast.

FIG. 3

FIG. 2

FIG. 1

FIG. 4

FIG. 5

FIG. 6

FIG. 8

FIG. 7
